UNITED STATES PATENT OFFICE.

JOHN M. BLONDELL, OF BALTIMORE, MARYLAND, ASSIGNOR TO FREDERICK E. TOBE, OF SAME PLACE.

DRAFT-POLE FOR HORSE-CARS.

SPECIFICATION forming part of Letters Patent No. 449,646, dated March 31, 1891.

Application filed August 7, 1890. Serial No. 361,380. (No model.)

To all whom it may concern:

Be it known that I, JOHN M. BLONDELL, a citizen of the United States, residing at Baltimore, in the State of Maryland, have invented 5 certain new and useful Improvements in Draft-Poles for Horse-Cars; and I do hereby declare the following to be a full, clear, and exact description of the invention, such as will enable other skilled in the art to which it appertains to make and use the same.

My invention relates to draft-poles for railway horse-cars; and it consists in certain novel parts and combinations of parts, the 15 separate features of which will be separately and specifically pointed out in the claims concluding this specification.

Referring to the accompanying drawings, Figure 1 represents in vertical section a draft-pole embracing my invention as coupled with the draw-iron and pole-support of a street-car. Fig. 2 is a top view of the draft-pole. Fig. 3 shows in separated relation the pole-socket iron and its separate coupling-eyed iron, and Fig. 4 shows the pole-socket iron.

20 In street-car poles the coupling-irons are subject to destructive wear and breakage, and when so rendered useless must be renewed by removing the pole-iron and rewelding thereto a new coupling-eye, and this requires the stripping of the coupling-irons from the pole to be renewed at the forge.

30 I make the coupling-pole iron of two parts, a bifurcated strap-iron part *a*, bolted to the pole in the usual way and terminating in a socket end *b*, and a coupling part *c*, having the eye *c'* for the coupling-pin adapted to be fitted and secured within said socket, so that coupling-eyed part can be easily removed and replaced when worn out without remov- 35 ing the pole-iron.

40 *d* is the pole, and *e* is a stay-brace to support the pole and hold it at a proper elevation, and *f g* the bolt and its guard for securing the whiffletree to the pole. I make this stay-brace with a vertical arm *e'*, having a screw-thread at its upper end, which passes through coincident openings in the pole-iron socket and in the coupling-eyed iron, and to which it is secured by nuts *h* above and be-

low the pole-coupling iron, and I prefer this 50 way of securing the coupling-eyed iron to the pole because it is convenient when a stay is used; but it is obvious that the coupling-eyed iron may be secured to the pole-iron by separate bolts *i* when a stay-brace is not used to 55 the pole.

The coupling-eyed iron is adapted to be coupled by the coupling-pin *j* with the car draw-iron *k*, and in connection with this coupling-pin and draw-iron I employ an adjustable stay-iron coupling *l* for coupling the stay-brace to the draw-iron by the coupling-pin for supporting the pole-iron upon the draw-iron coupling-pin. For this purpose I secure the stay-coupling iron *l* near the lower 60 end of the stay-brace arm, and I provide the draw-iron with a lower projecting arm or bracket *m*, having an eye to receive the coupling-pin, whereby the pole is supported and held in a horizontal position to the draft and 65 the front end of the pole prevented from flying up or down by the movements of the horses. This lower supporting-coupling stay-iron, in connection with a coupling-pin, passes through the upper and lower arms or jaws of 70 the draw-iron, serves to prevent the snapping off of the upper arms or jaws of said draw-iron, which otherwise would be liable by the flying up or down of the pole, and make this 75 lower stay-coupling iron adjustable by its screw-threaded end and the double nuts *n* on each side of the brace-stay arm, so that the stay-coupling can be lengthened and shortened and to adapt it for other coupling-irons in use. I also provide for adjusting the lower 80 or stay-coupling iron vertically by means of its threaded arms and nuts for the purpose of adapting said stay-coupling iron to cars 85 having various-sized coupling-irons.

A stay-brace for the draft-pole of a horse-car is very old as a separate braced attachment to the pole and coupled to the car by a coupling-pin distinct and independent from the pole-coupling pin, and a coupling-iron for a doubletree has been formed with an eye at 90 one end to receive the coupling-pin of the draw-iron and at its other end with eyed jaws by which it receives the doubletree and its 95

pivot-pin, and such doubletree-coupling iron has been formed with a brace separately pivoted to the draw-iron.

I claim as my improvement—

- 5 1. The combination, with a draft-pole, of a coupling-iron therefor composed of a strapped part terminating in a socket end, an eyed part fitting said socket, and a stay-brace having a vertical arm passing through and bolted to the socket-connected parts.
- 10 2. The combination, with a draft-pole, of a stay-brace having a coupling-iron, means for vertically adjusting said stay-brace, and means for horizontally adjusting said coupling-iron.
- 15

3. The combination, with a draft-pole, of a stay-brace having a vertical screw-threaded arm, the nuts for securing it to said pole, and a screw-threaded coupling-iron on said stay-brace having double nuts, whereby a vertical ²⁰ and horizontal adjustment may be made of the supplemental coupling parts.

In testimony whereof I affix my signature in presence of two witnesses.

JOHN M. BLONDELL.
